UNITED STATES PATENT OFFICE.

JOHN M. HANSEN, OF PITTSBURG, PENNSYLVANIA, ASSIGNOR TO FORGED STEEL WHEEL COMPANY, OF PITTSBURG, PENNSYLVANIA, A CORPORATION OF PENNSYLVANIA.

APPARATUS FOR FORGING CAR-WHEEL TREADS.

No. 866,022.

Specification of Letters Patent.

Patented Sept. 17, 1907.

Application filed May 19, 1906. Serial No. 317,736.

To all whom it may concern:

Be it known that I, JOHN M. HANSEN, a resident of Pittsburgh, in the county of Allegheny and State of Pennsylvania, have invented a new and useful Improvement in Apparatus for Forging Car-Wheel Treads; and I do hereby declare the following to be a full, clear, and exact description thereof.

My invention relates to dies for forming wheel blanks, its object being to provide suitable dies for forging a previously formed wheel blank and forming on the same a combined tread and flange, the apparatus being suitable for carrying out part of the method described in an application filed by me of even date herewith, Serial No. 317,733. In connection with the 15 said method set forth in said application a blank is formed having a rim or tread forming portion projecting in line with the axis of the blank.

The main object of the present invention is to so forge said rim portion as to develop from the same 20 rim, a tread and flange of the wheel, and subject the same to such work as to condense the metal of said tread and flange, compact it and obliterate any flaws contained in it and produce a tough, strong flange of high wearing qualities.

It comprises, generally stated, a male die having an annular projecting portion to support the web of the blank, and substantially vertical side walls against which the rim portion of the blank fits, together with a central hub recess, and corresponding dished or 30 female die having a hub cavity, an inclined web forming face outside of the hub cavity, and an annular flange forming recess, and means for forcing the tread portion of the blank inwardly to form the tread and outwardly to form the flange, such as an annular following die around the male die provided with an annular recess having an outwardly inclined face conforming to the shape of the tread of the wheel and flaring flange forming recess beyond the same.

It also consists in the combination of certain parts of 40 the die construction above outlined, as hereafter more fully set forth and claimed.

In the accompanying drawings Figure 1 is a vertical section showing the different parts of the dies, the blank being confined between the male die and the 45 female die, and before the forging of the rim; Fig. 2 shows the dies after the forging of the rim; Fig. 3 is an enlarged detail view of a portion of the wheel showing it after forging in full lines, and before forging in dotted lines; Fig. 4 is a view of the dies where 50 the outer annular die is connected to and forms part of the male die, the dies being open; and Fig. 5 is a like view of the dies closed.

In order to make clear the operation of the said dies I will describe the blank operated upon and the con-

struction of the dies and the steps followed in forging 55 the same. The original blank with which it is preferred to employ my invention is prepared by a previous die forging operation fully described in said application Serial No. 317,733, said blank having the central hub portion 1, the web portion 2 and the rim 60 or tread forming portion 3, said tread forming portion containing sufficient metal for the development of the tread with its flange, and said tread forming portion extending substantially parallel with the axis of the blank. As the blank is first forged it may be of suitable internal diameter to fit over the male die 4 or slightly less than that so that when the blank is clamped between the male die 4 and the female die 5 it may be spread somewhat as its tread forming portion 65 is forced around the male die 4. This blank is 70 raised to a suitable forging heat and is then placed over the male die 4 and the female die 5 is brought down upon it, clamping it ready for the tread forging step, as shown in Fig. 1. The male die 4 has the curved annular projection 6 and the central hub cavity 7 into which a portion of the hub 1 enters as shown. It also has the central opening 8 into which the mandrel 9 fits, said mandrel 9 as illustrated in said figure, preferably passing through a like opening in the female die 5, and being independently operated by the 80 said dies, so that it supports the eye of the hub. The female die 5 has the hub cavity 10 to envelop and support the hub projecting on that side of the blank. Beyond the same is the curved concave die face 11 connected to the hub cavity by a curved face, this 85 die face 11 confining the web portion of the blank. Beyond said die face 11 is the annular flange forming recess 12, separated from the web face 11 by the curved annular projection 13.

Back of the curved annular projection 6 of the male 90 die is the vertical face 14 and fitting around the same is the annular tread forming die 15 having the tread forming cavity 16 shown as provided with a straight base 17, and having the outwardly inclined tread forming face 18 conforming in shape to the tread of 95 the wheel, while beyond the same is the flaring flange forming cavity 19. It will be noticed that the space between the vertical face 14 of the male die and the inclined face 18 of the tread forming cavity 16 is narrower than the thickness of the rim or tread forming 100 portion 3 of the blank. Therefore when said die 15 is forced toward the female die 5 its first action is to upset the tread forming portion of the blank by first forcing it inwardly toward the web portion of the blank. This brings great pressure and work upon the 105 tread forming portion of the blank acting with great pressure upon the tread face, so as to highly compress the same and cause the metal to flow inwardly and

backwardly to fill the flange forming cavity formed by the annular recess 12 in the female die and the flaring recess 19 of the annular follower die 15, the metal being thus first forced inwardly and backwardly so as to form the tread of the wheel blank and to center the tread with relation to the web, and then to spread the metal out into the said flange forming cavity, so completing the formation of the tread and flange of the wheel, and distributing the metal properly throughout this portion of the blank. In this way heavy work is brought upon the tread of the blank, compacting and hardening it and developing the desired fiber structure therein to give high wearing qualities. In these dies, if desired, further compression may be brought upon the hub portion of the blank, bringing it to exact finished shape. To complete the wheel it is only necessary to properly dish it, giving the desired reverse curve to the web and setting the hub and tread in proper relation as described in said method application, Serial No. 317,733, it being preferred that this operation is performed when the wheel is at a lower temperature, and that a further upsetting of the tread and flange portion of the wheel and further densifying and compacting thereof take place, as described in said application.

The dies in Fig. 4 show a modification of the invention in which the female die 22 is of substantially the same shape as shown in the other figures, but the male die and tread forming die are formed in one, the curve of the annular projection 23 of the male die 24 meeting at the base of the tread forming cavity 25 while beyond the same is the outwardly inclined face 26 extending to the outwardly flaring flange forming cavity 27. The mandrel 28 extends upwardly through the female die which in this case is the anvil die, that die having the hub forming cavity 29, the web forming or supporting face 30 and the annular depression 31 acting with the flaring cavity 27 to form the flange cavity. In the use of this form of dies the blank can be of substantially the same shape as that shown in connection with the other figures, or it may be such as shown in said Fig. 4, the rudimentary hub portion 32 extending wholly on one side of the blank so that as the dies are brought together this rudimentary hub may be upset between the hub forming or supporting cavities 29 and 29^a, and the completed hub thus formed from the rudimentary hub 32 while the rim forming portion 34 is upset within the tread

forming cavity and the flange forming cavities in substantially the same manner as above described in connection with the other figures. 50

What I claim is:

1. Dies for forging wheel treads or rims having clamping faces adapted to clamp the web portion of the blank, one of the dies having an annular outwardly inclined forging face conforming in shape to the tread of the wheel, and acting to force the metal inwardly and so compact the metal while forming the tread face of the wheel. 55

2. Dies for forging wheel treads or rims having clamping faces adapted to clamp the web portion of the blank, one of the dies having an annular outwardly inclined forging face conforming in shape to the tread of the wheel, and acting to force the metal inwardly and so compact the metal while forming the tread face of the wheel, and having a flaring flange forging face beyond the tread forging face, the opposing die having an annular flange forging recess beyond its web clamping face. 60 65

3. Dies for forging wheel treads or rims, having male and female web clamping faces, one of the dies having an annular outwardly inclined forging face conforming in shape to the tread of the wheel and acting to force the metal inwardly and so compact the metal while forming the tread face. 70

4. In apparatus for forging wheel treads, the combination of a female die having a hub cavity and an inclined web clamping face outside thereof, a male die having an annular curved web clamping projection, and an independently acting annular follower die around the male die and provided with an outwardly inclined tread forging face conforming in shape to the tread of the wheel and acting to force the metal inwardly and backwardly and so compact the metal while forming the tread face of the wheel. 75 80

5. In apparatus for forming wheel treads, the combination of a female die having a hub cavity, an inclined web forming face outside thereof, and an annular flange forming recess, a male die having an annular curved projection and an independently acting annular follower die around the male die provided with an annular recess having an outwardly inclined tread forging face and a flaring flange forging face beyond the same. 85 90

6. Dies for forging wheel treads or rims shaped to hold the rim portion turned toward one side, and having clamping faces to clamp the web portion of the blank, one of the dies having an annular outwardly inclined forging face conforming in shape to the tread of the wheel, and acting to force the metal of the turned rim portion inwardly and thereby compact the metal while forming the tread face of the wheel. 95 100

In testimony whereof, I the said JOHN M. HANSEN have hereunto set my hand.

JOHN M. HANSEN.

Witnesses:
